UNITED STATES PATENT OFFICE.

CARL MORU, OF KENOSHA, WISCONSIN, ASSIGNOR TO THE BADGER BRASS MFG. CO., OF KENOSHA, WISCONSIN, A CORPORATION OF WISCONSIN.

LAMP STRUCTURE.

1,128,893.

Specification of Letters Patent. Patented Feb. 16, 1915.

Application filed June 5, 1914. Serial No. 843,160.

To all whom it may concern:

Be it known that I, CARL MORU, a citizen of the United States, and a resident of Kenosha, in the county of Kenosha and 5 State of Wisconsin, have invented certain new and useful Improvements in Lamp Structures, of which the following is a specification.

This invention relates to improvements in 10 lamp structures and process of making same, and refers more particularly to an improved form of combined reflector and locking ring for holding the glazing in position, and to a new and useful manner of making same.

15 The process or method employed in the manufacture of the reflector and the locking ring forms the subject matter of another application, Serial No. 876,231, filed December 9, 1914, which is a division of this, my 20 original application.

Among the salient objects of the invention are to provide a construction in which the parabolic reflector, the glazing and the lamp-body are locked together in assembled position by means of a single locking member; to provide a construction of the type described in which the locking member is positively prevented from becoming loose, due to vibration or other causes; to provide a construction in which the locking member itself forms an important element tending to improve the general ornamental appearance of the lamp; to provide, in a construction of the type referred to, a locking member which 30 may be readily adjusted in position, which will positively lock the parts together when adjusted, and prevent the ingress of dust or corrosive vapors; and in general to provide an improved construction of the character 35 referred to.

In the drawings, Figure 1 shows in elevation a small automobile headlight embodying my construction; Fig. 2 is a section along the line 2-2 of Fig. 1; Fig. 3 is a fragmentary section of the ends of the locking ring and associated locking means; and Fig. 45 Fig. 4 is a fragmentary enlarged view of the lower portion of Fig. 2; Fig. 5 is a plan view showing the reflector and the locking ring 50 during one of the initial stages of manufacture; Fig. 6 is a fragmentary section along the line 6 of Fig. 5; Fig. 7 is a fragmentary

section of the reflector and locking ring at a later point in the manufacturing process; Fig. 8 is an axial section of the finished reflector bowl; and Fig. 9 is a plan view of the locking ring after the last forming operation.

Referring to the drawings, 1 represents the outer shell of the lamp, which, as shown, 60 is stamped or spun from a single piece of metal, and is so shaped as to completely inclose the reflector 2. To each side of the lamp is riveted a boss 3, which is provided with a vertical hole to fit one of the lamp 65 forks. The outer edge of the shell 1 is rolled over to form a finishing bead 3 at the edge of the flaring portion of the lamp, and within the latter are formed the circumferential seat 4 for the reflector and the circumferential groove 5, within which is seated the locking ring 6. The parabolic reflector 2 is suitably orificed at the rear to admit the lamp-socket 7, the lamp proper being indicated in dotted lines at 8, and the front edge 70 of the reflector is pressed out to form a flanged portion 9 of the proper diameter to seat in the circumferential recess 4 of the outer shell. Shellacked or otherwise suitably cemented to the outer edge of the flange 75 9 of the reflector is an annular dust-gasket 10, against which the glazing 10° is forced by the action of the locking ring 6, and which seals the interior of the lamp against the ingress of dust particles.

Referring now to the specific construction of the locking means, it will be seen from an inspection of Fig. 3 that one end of the locking ring 6 is expanded for a short distance from its end to provide a telescopic sheath 90 portion 11, which laps over the other end 12 of the locking ring and is adapted to slide thereon when the two ends of the locking ring are forced apart. Circumferential movement of the fixed end 12 of the locking ring is prevented by a pin 13 which is engaged by the end of a block 14 which is soldered to the under side of the end 12 of the locking ring. To the outer shell of the lamp is riveted a hollow box-like stamping 100 15, which forms a slide for the outer end of a wedging dog 16. The outer end of the latter is tapped to receive a locking screw 17, which passes through a small hole in the

end of the slide-box 15 and engages the outer end of the latter when the wedging dog 16 is pulled circumferentially by the screw. The inner end of the wedging dog 16 is formed with an inwardly-extending cam-hook 18 which engages the end of a small punching 19 soldered to the movable end of the locking ring. The hook end 18 passes through and slides in a circumferentially extending slot 20 in the outer shell. In assembling the various parts of the lamp, the reflector 2 is first placed in its seat in the outer shell 1 and the glazing applied to the end of the reflector. The locking ring is then inserted by first placing the end 12 in the circumferential groove 6 of the outer shell in such a position that the block 14 engages the pin 13. The remaining portion of the circumference of 20 the locking ring is then worked into the slot, pressure being at the same time maintained in a direction to hold the block 14 against the pin 13, and finally the free end of the locking ring drops into the groove. 25 It should be noted that, before the locking ring can be assembled, it is necessary to unscrew the catch member 18 to its fullest extent, so that it will not interfere with the member 19 to prevent the free end of the 30 locking ring from entering the groove. When the locking ring is in place, it is then positively locked in position by screwing up the member 18 into the position shown in Fig. 3. To remove the ring, after loosening the screw 17 and forcing back the wedging dog 18, it is necessary to insert the point of a knife or other instrument between the overlapping portion 11 of the locking ring and the outer shell. 40 The locking ring 6 is formed of nickeled brass or other metal capable of taking a good finish, and is of such width and shape as to form an ornamental trim around the glazing opening, harmonizing with the general shape of the lamp. The depth of the section is also such that when the locking ring is forced tightly outward, due to the action of the wedging dog 16, the glazing and reflector are wedged tightly in position, 45 and the construction is thereby rendered very secure and free from rattle or the possibility of vibration loosening up any of the parts.

The process of making the locking ring and reflector, which forms an important feature of my improved lamp construction, will now be described. Briefly, the process consists in manufacturing the parabolic reflector and the locking ring from a single blank, the parabolic reflector being formed concentric with and within the locking ring, which is afterward severed from the reflector and then divided radially and formed as to its two ends so as to provide 50 an overlapping ring of the proper diameter.

Referring to Fig. 5, 21 represents a blank of brass or other suitable material after the combined reflector and locking ring have been formed to the proper shape, before the trimming operation. This initial forming ordinarily consists of two or three punch-press operations with dies which are suitably graduated in shape, in order to prevent tearing of the metal. During these preliminary forming operations, the metal around the exterior of the circular formed portion of the blank must be held very securely against inward radial creeping movement due to the action of the dies, and in order to do this, it is necessary to provide around the edges of the circular portion enough width of metal so that pressure may be applied to the exterior of the blank by means of suitable spring pads to prevent this creeping action. This always results in a great loss of material when making a reflector or similarly formed part. The making of the locking ring as a single part would result naturally in a similar waste of material. It will thus be self-evident that by forming the reflector and the locking ring in a single piece, I effect a saving in material equal to the size of a blank large enough to make the reflector alone, besides effecting a considerable reduction in the number of forming operations. After the blank attains the shape shown in Figs. 5 and 6, it is then subjected to a trimming operation, which removes the corners 22 and also punches the hole 23 in the bottom of the reflector bowl. After the combined ring and bowl have thus been trimmed, it is sometimes necessary to perform an additional beading operation, which gives the required shape to the outer edge of the locking ring, as shown at 24 in Fig. 7. After the blank has reached the shape shown in Fig. 7, the locking ring is severed from the bowl by cutting the blank at 25, this operation usually being performed in a lathe by means of a narrow parting tool. This leaves the reflector-blank in its finished condition, as seen in Fig. 8. In order to enable the locking ring to occupy the position which it does occupy in the finished lamp structure, as shown in Figs. 2 and 4, it is necessary to effect a considerable reduction in its diameter, which is accomplished by cutting the ring radially and removing a portion of its circumference, the ends being overlapped, as shown in Fig. 9, so that the locking mechanism for the ends of the ring may be applied. Owing to this reduction in the diameter of the ring when it occupies its position in the lamp, the ring itself has a very strong tendency to spring outwardly and resume its original diameter. This results in a very secure and substantial construction, which is rendered doubly effective.

tive by the locking means previously described.

I do not limit myself to the details of construction shown except as specified in 5 the appended claims.

I claim:

1. In a lamp, the combination of an outer cup-shaped casing provided at its outer end with an inner annular glazing seat and an 10 outer annular seat axially displaced with reference to said first seat, a glazing seated on said inner annular seat, a sheet metal non-continuous locking ring adapted to engage said outer seat and force the glazing 15 into engagement with said first seat, and means located wholly behind and concealed by said ring for locking said ring in position.

2. In a lamp, the combination of an outer 20 casing provided at its outer end with an inner annular seat and an outer annular seat axially displaced with reference to said first seat, a glazing on said inner annular seat, a resilient pressed sheet metal non-continuous 25 locking ring provided with overlapping ends and adapted to engage said outer seat and force the glazing into engagement with said first seat, and means wholly behind, concealed by, and operable from the rear of 30 said ring to positively expand said ring tangentially.

3. In a lamp, the combination of an outer cup-shaped casing provided at its outer end with an inner annular seat and an outer annular seat opposed to and axially displaced 35 with reference to said first seat, a glazing on said inner annular seat, a pressed sheet metal non-continuous locking ring adapted to engage said outer seat and force the glazing 40 into engagement with said first seat, said casing being adapted to form a pocket behind said ring, and means within said pocket operable from the exterior of the casing to expand said ring tangentially.

4. In a lamp, the combination of an outer 45 bowl-shaped casing provided at its open outer end with an inner annular outwardly facing seat and an outer annular inwardly facing seat opposed to and axially displaced with reference to said first seat, a parabolic reflector provided with an outwardly projecting flange adapted to engage said inner seat, a glazing adapted to engage the outside of said flange, a pressed sheet metal 55 non-continuous locking ring provided with overlapping ends and adapted to engage said outer seat and force the glazing toward said inner seat, said ring being provided with an inwardly projecting annular lip 60 adapted to engage said glazing and form an ornamental trim around the glazing, said ring, glazing, and casing forming a hollow annular pocket, and screw-operated means located behind, concealed and protected by 65 said ring and within said pocket, operable

from behind said trim, for positively expanding said ring tangentially.

5. In a lamp, the combination of an outer casing, a glazing seated within said casing, a non-continuous locking ring for holding 70 said glazing in position, the ends of said locking ring overlapping, and a screw-operated dog member for engaging one of the ends of said ring to lock the latter in position. 75

6. In a lamp, the combination of an outer casing provided with a circumferential groove, a glazing seated within said casing, a non-continuous locking ring for holding 80 said glazing in position and seated within said groove, the ends of the locking ring overlapping, means for preventing circumferential movement of one of the ends of said locking ring, and a screw for holding apart the two ends of said ring and locking 85 it in position.

7. In a lamp, the combination of an outer bowl-shaped casing provided with an annular seat, a glazing on said seat, a non-continuous sheet metal locking ring adapted to 90 hold said glazing in position and to form an ornamental trim around the glazing opening, and provided with means whereby the opening between the ends of the ring remains sealed when said ends are moved apart, and 95 screw-operated means for forcing apart the ends of said ring in a tangential direction.

8. In a lamp, the combination of an outer casing, a glazing seated within said casing, a non-continuous locking ring for holding 100 said glazing in position, said locking ring being provided with overlapping ends, and means for locking the overlying end in position.

9. In a lamp, the combination of an outer 105 casing, a glazing seated within said casing, a non-continuous locking ring for holding said glazing in position, said locking ring being provided with overlapping ends, and means for locking the overlying end of said ring in engagement with the end beneath. 110

10. In a lamp, the combination of an outer cup-shaped casing provided at its open outer end with an inner annular seat and an outer annular opposed seat axially displaced with 115 reference to said first seat, a parabolic reflector provided with a circumferential flange adapted to engage said inner seat, a non-continuous locking ring adapted to engage 120 said outer seat and force the reflector flange into engagement with said first seat, a glazing interposed between said ring and said flange, and positive means for locking said ring in position, said means including means for positively positioning one of the 125 ends of said ring, and means carried by the casing for clamping the other end of said ring.

11. In a lamp, the combination of an outer 130 bowl-shaped casing provided with an inner

- annular outwardly facing seat and an outer inwardly facing locking ring seat axially displaced with reference to said first seat, a parabolic reflector nested within said outer 5 casing and provided with an outwardly projecting annular flange adapted to engage said inner seat, a glazing adapted to engage said flange and close the end of the reflector, a pressed sheet metal annular locking ring 10 provided with an outer curved portion adapted to engage said outer seat and with an inner inwardly projecting annular lip adapted to engage the outer face of the glazing and force the latter toward the inner 15 seat, said locking ring forming an ornamental trim around the glazing, said ring, glazing, and outer casing forming a substantially weatherproof annular cavity, means within said cavity adapted to engage 20 each end of said ring and resist relative movement thereof toward each other, and a screw operating on said means and adapted to cause relative movement away from each other in a tangential direction.
- 25 12. In a lamp, the combination of an open-ended outer casing, a glazing seated within said casing and adapted to close the end

thereof, a non-continuous locking ring for holding said glazing in position, means for positioning one of the ends of said locking 30 ring, against movement toward the other end of said ring, and independent means for locking the other end of said ring in position.

13. In a lamp, the combination of an open-ended outer casing, a glazing seated within said casing and adapted to close the end thereof, a non-continuous locking ring for holding said glazing in position, stationary 35 means for positioning one of the ends of 40 said ring, and adjustable means for holding the other end of said ring in position.

14. In a lamp, the combination of an outer casing, a glazing seated within said casing, a non-continuous locking ring for holding 45 said glazing in position, a stationary member adapted to engage one of the ends of said ring to prevent movement of the latter, and screw-operated means engaging the other end of said ring.

CARL MORU.
